UNITED STATES PATENT OFFICE.

DAVID A. LANDERS, OF CHICAGO, ILLINOIS, ASSIGNOR TO WIREBOUNDS PATENTS COMPANY, OF KITTERY, MAINE, A CORPORATION OF MAINE.

MACHINE FOR USE IN MAKING BOXES.

Application filed September 13, 1919. Serial No. 323,450.

To all whom it may concern:

Be it known that I, DAVID A. LANDERS, a citizen of the United States, residing at Chicago, in the county of Cook and State 5 of Illinois, have invented new and useful Improvements in Machines for Use in Making Boxes, of which the following is a specification.

My invention relates to machines for use 10 in making boxes, crates or the like and particularly for use in making wirebound boxes, crates, blanks or parts thereof.

Among other objects, the invention is intended to provide improved mechanism for 15 positioning the staples or fasteners by which the box materials are secured together and the binding wires attached thereto.

The invention will be described by reference 20 to an illustrative embodiment shown in the accompanying drawings, in which—

Fig. 1 is a side elevation of one end of an approved type of wirebound box-blank machine embodying my invention.

Fig. 2 is a longitudinal vertical section of 25 the same illustrating a finished box blank being delivered from the machine and assembled box sections for a succeeding blank to be operated upon.

Fig. 3 is a detail view, in cross section, 30 of one of the work-conveying chains and its supporting guide.

Fig. 4 is an enlarged side view of the feed and staple positioning mechanism.

Fig. 5 is an enlarged side view of the 35 staple positioning mechanism showing a correcting device for the same.

A box blank machine consists generally of a gang of binding-wire applying and stapling mechanisms for wiring together box 40 sections on a work support, the two being relatively movable for stapling the wires at intervals depending upon the progression of the work between successive operations of the staplers.

In the illustrative machine, the staplers 45 and associated mechanisms, one complete unit of which is shown in Fig. 2, are relatively stationary in the side frames 1, and the work is supported and advanced by a conveyor 3 comprising link side chains appropriately formed to receive the cleats of 50 the box sections, said chains running in

guides 5 on supporting rails 6 and trained around the driven sprocket wheels 7.

Cleats and superposed sheets of side material composing box sections are assembled 55 on the conveyor chains in proper relation to provide a box blank or blanks, the sections of each blank being held in proper position on the chains by spacer blocks 4 60 attached at intervals on the side bars of individual chain links, as shown in Fig. 3. As the work progresses beneath the staplers, a plurality of continuous binding wires, drawn from suitable supply reels, not shown, 65 are introduced in proper relation to the box sections to be stapled thereto, the wires being led between the rollers 9 and thence under the rollers 10 at the feet of the stapler bodies, and being pulled along with the work 70 by virtue of their attachment thereto at preceding points. Certain of the wires aligned with the box cleats are stapled through the sheets thereto, so as to connect such wires to both the sheets and cleats and secure the 75 latter together; and intermediate wires are or may be stapled to the sheets alone and clinched on their under sides by co-action of the staple drivers with anvils 12 supported on the cross frame member 11. 80

The illustrated staplers 13 are of the type disclosed in the patent to Thompson, No. 1,258,625, dated March 5, 1918, comprising staple formers and drivers adapted at every operation to cut and form staples from 85 staple stock wire, fed thereto by rollers 14, and to drive the same over the binding wires into the work. Said staplers are mounted on the stationary cross-head 15 and actuated by the vertically reciprocating cross-head 16, working in guides 17 of the side frames 1, and operated by a pitman 18 from an eccentric 19 on the main shaft 2, there being a similar operating connection at either side of the machine. The feed rollers 90 14 for the staple stock wire are also operated from the main shaft by an eccentric 20 and a connecting rod 21 working a pawl and ratchet device 22 for rotating the rollers intermittently. 95

It will be understood that a staple is formed and driven at every reciprocation of the cross-head 16, the staple being driven on the downward stroke thereof while the ma- 100

terial is momentarily at rest, the extent of movement of the material between the successive operations of the staplers determining the spacing between successive staples.

5 Step-by-step movement is imparted to the conveyor by a regulable feed mechanism, the movements being automatically controlled for positioning staples in desired relation on the work. As illustrated, the 10 feed mechanism comprises the pawl-driven ratchet wheel 23 secured to one of the sprocket wheels 7 or on the sprocket shaft 8, and the oscillating driving arm or lever 24 connected to the pawl carrying lever 27 15 by the toggle bars 25 and 26. For the purpose hereinafter described toggle bars 25 and 26 are pivoted respectively to the driving lever 24 and the pawl carrying lever 27 and are also pivotally connected together 20 by the pin 32. The pawl carrying lever 27 carries one or more feed pawls 28 pivoted thereto on the pin 29 and preferably spring held toward the ratchet teeth. The driving lever 24 and the pawl carrying lever 27 are 25 loosely mounted on the sprocket shaft and are worked to and fro by the connecting rod 30 from eccentric 31 on the main shaft 2. On the working stroke the feed pawl engages and rotates the ratchet wheel advancing the conveyor a corresponding amount. 30 Thus a regular step-by-step movement of the conveyor is provided.

For variably determining or controlling the feed movements, mechanism is provided 35 to break the toggle connection between the driving lever 24 and the pawl carrying lever 27 during a driving movement of the lever 24, thereby terminating the actuation of the pawl carrying lever 27 and the travel of the 40 conveyor. Said mechanism may comprise a series of controlling members constituting pattern means and herein exemplified as variable length pins or stops 41 set in a rotating disc 42 and arranged to be successively 45 presented in the path of a reciprocating bar 39 which is operatively connected to and actuated by arm 40 of link 38, the latter connected to lever 33 loosely mounted on the sprocket shaft 8. Said lever 33 is attached 50 to or unitary with another lever 34, which may be termed a positioning lever, and which is provided with a forked end constituting toggle throw-out arms 35 and 36. The pin 32 connecting the toggle bars 25 55 and 26 is normally held in the notch between arms 35 and 36 by spring 43 connecting said pin 32 and lever 33, so that normally said toggle bars are held in position to impart motion from the driving lever 24 to the 60 pawl carrying lever 27. Upon the working stroke of the driving lever 24, the levers 33 and 34 and the link 38 travel therewith, until the bar 39 strikes one of the controlling pins or stops 41. The lever 33 is then 65 rested and, upon continued movement of

the driving arm 24, the pin 32 rides outwardly on the inclined plane of the toggle throw-out arm 35, thus breaking the toggle connection between the driving lever 24 and the pawl-carrying lever 27 and permitting the driving lever 24 to complete its working stroke without imparting further motion to the feed pawl 28. Upon the return or inoperative stroke of the driving lever 24, the pin 32 will return to its normal position 70 between arms 35 and 36, re-establishing the toggle connection, and will move the levers 33 and 34 and consequently the bar 39 back to position for the next forward stroke. During this return movement the pawl-carrying lever 27 will also be returned, the pawl 28 clicking idly over the ratchet teeth of the wheel 23. Thus it is clear that the duration of the driving connection between toggle bars 25 and 26 determines the period 75 or duration of the movement of the ratchet wheel and the conveyer, and that the control or breaking of the toggle connection enables regulation of the cessation of relative feed movements of the work. 80

It will be noted that in the illustrative construction thus described, the driving lever has a constant stroke, while its operative effect is regulated or varied by controlling the connection between the driving 85 lever and the pawl carrying lever, said connection being broken at selected times during the working stroke of the driving lever. In other words, there is provision for lost motion between driving and driven means 90 of the feed mechanism, said lost motion being variably initiated during the working stroke and terminating its operative effect, i. e. discontinuing the feed. Among other advantages this construction permits the feed to start at the slowest movement of the actuating eccentric, that is to say at the beginning of the throw of the eccentric, thus avoiding excessive shock. 95

The disc or turret 42 carrying the controlling pins or stops 41 is mounted on a shaft 37 suitably journaled in the side frames 1. Said disc has a series of bores in which the pins are fitted and secured by set-screws 44. They are adjusted to project 100 from the outer rim of the disc variable distances to correspond with the length of feed steps desired between fasteners. As many pins are thus set in the pin disc as there are fasteners to be driven in one box blank, so that the position of each fastener in the blank is controlled. Each pin 41 is presented in succession into the path of travel of the reciprocating bar 39, thereby causing the toggle connection to be broken and discontinuing the further movement of the work 105 until after another fastener has been driven into the work. It is obvious that the length of the projection of a pin 41 from the outer rim of the disc 42 determines the point of 110

115 120 125 130

stoppage of the bar 39. A long projection, therefore, produces a short feed step and vice versa.

For successively presenting the pins 41 into the path of the bar 39, the disc 42 (see Figs. 1 and 4) is revolved in a clockwise direction, at appropriate speed, by a continuously operating friction belt 45 connected to a pulley 46 on the main shaft 2.

10 A spring pressed latch 47 (see Fig. 2) pivotally connected to arm 49 and working in guides 48 suitably secured to the frame of the machine is normally held by its spring 50 in the path of travel of the set screws 44 to arrest the movement of the disc 42 as each pin 41 is presented in position to stop the bar 39; the belt drive meanwhile slipping. The latch 47 is automatically withdrawn at proper intervals to permit the further movement 15 of the disc 42 to present the next pin 41 to the bar 39.

For causing said latch 47 to be automatically withdrawn temporarily at proper intervals to permit the successive presentation of the pins 41, its operating arm 49 which is pivoted at 51 is connected by link 52 to arm 53 pivoted at 54 and carrying at its lower end a trip finger 55 pivoted to swing in one direction only, that is to the left from its position in Fig. 2. The spring 56 yieldingly holds the trip finger 55 in its normal vertical position in the path of travel of a lug 57 carried by bar 39. As the bar 39 travels to the left from its position in Fig. 2, the lug 57 displaces and passes under the trip 55 without any operative effect upon the latch, and the spring 56 returns the trip finger to its original position. The bar 39 continues its travel to the left until stopped by the pin 41 which is being held in position by the latch 47 acting on the set screw 44. Upon the return movement of the bar 39 the lug 57 contacts with the trip finger 55 and carries it to the right (see Fig. 2). This movement swings arm 53, link 52 and arm 49 and withdraws latch 47 from its position of contact with set screw 44. Immediately disc 42 resumes its movement, carrying the set screw 44 past latch 47. The lug 57 carried by the bar 39 quickly passes and releases finger 55 permitting latch 47 to snap back into position to engage and hold the next set screw 44. It will be noted that the withdrawal and return of the latch 47 is accomplished so quickly that the pins 41 and their set screws 44 may be located on the disc 42 in as close relationship as may be necessary. It will also be noted that by reason of the relatively high speed of the disc 42 by its friction drive said pins 41 may be spaced considerable distances apart. In other words, the relative position of the pins 41 on the disc 42 do not necessarily have to be regular or uniform; the feed movements of the conveyor which locate the fasteners in the work

being controlled by the length of said pins and not by the spaces intervening between them.

As represented in Fig. 2 the machine is operating upon blanks of four sections of alternate widths, there being fourteen staples per blank, three on the narrow and four on the wide sections, and the pin-carrying disc is accordingly provided with fourteen pins. More or less pins may be employed depending upon the number of staples desired in a box blank.

For definitely locating staples in a blank, therefore, the operative may plot in any suitable way the desired staple positions, for instance, he may conveniently lay off roughly or by eye on a sample blank or the first blank assembled on the machine, the desired stapling points and measure their distances apart. He may then adjust the set of pins 41 in a corresponding relationship at proportional distances from the rim of disc 42 with the effect of proportionally subtracting from the otherwise normal or possible maximum feed steps, and, accordingly, bringing the work successively to rest at positions corresponding to the plotted positions of the staples. To facilitate the adjustment of the pins, graduations may be provided on the pins, the graduations being for instance in the same ratio to standard units of lineal measurements as the ratio of the maximum feed stroke to the step-movements of the conveyor imparted thereby. The rim of the disc 42 provides a definite index with respect to which adjustments may be made.

After the adjustment of the pattern of controlling pins, the first blank to be stapled may be adjusted with reference to the stapling mechanism so that the first feed-step controlled by the first pin will bring the work to locate the first staple at the proper or desired point; which may be done by preliminary advancing the conveyor chains with the assembled work to the proper position. Thereafter the succeeding staples of the blank will be automatically positioned properly by the successive step movements corresponding to the lengths of the pins. However, by virtue of an automatic correcting means hereinafter described, such preliminary adjustment of the work is not essential.

As heretofore stated the disc 42 is set with the requisite number of controlling pins for one blank. The illustrative machine, however, is designed for continuous operation upon a succession of box blanks which are positioned on the conveyor chains 3 by means of the spacer blocks 4, a sufficient space being provided between blanks to insure the necessary extension of wire at each end of the completed blank to be twisted or otherwise secured together when the blank

is folded into box form. Such spaces are usually of greater length than the length of a maximum feed step so that after the last staple is driven in a blank two feed steps 5 are usually required to bring the following blank to staple receiving position. If the spaces between blanks were at all times uniform, the feed step between blanks could be controlled by the insertion of an additional pin 41 in the disc 42. To insure uniformity of spaces between blanks, however, it is necessary that the conveyor chains 3 be of a length exactly equal to some multiple of the length of one box blank plus 10 the space between blanks, and while the conveyor chains 3 may be lengthened or shortened by adding or removing certain of the links of the chain, nevertheless it is found very difficult and almost impossible 15 to practice to accurately adjust the length of the chains for boxes of different dimensions so that the length of the chains will be an exact multiple of the length of one blank plus the length of the spaces between 20 blanks. It is desirable, therefore, to provide a correcting or adjusting mechanism which will automatically control the feed step between blanks, regardless of the uniformity of spaces between blanks, so that 25 30 the next feed step, which is controlled by the initial pin of the pattern of pins, will properly locate the first staple of the succeeding blank. Such a mechanism is therefore provided to effect a relative adjustment 35 between the pattern of pins and the work movement for rectifying inaccuracies due to variations in the lengths of the blanks or the spacing thereof, and to insure accurate positioning of staples upon successive 40 blanks.

The illustrative correcting mechanism (see Fig. 5) comprises an arm 58 having a beveled end 59. Said arm is loosely mounted on the shaft 37 so that its beveled end 45 may be swung downwardly across the path of travel of the bar 39. Said arm is connected to the shoe or weight bar 60 by the links 61 and 62. The shoe or weight bar 60 rides on top of the blank material 50 to press it down and hold it in position on the conveyor chains and is secured to the frame of the machine by retractile spring 63. A latch or detector 64, pivotally connected to the weight bar 60 by the pin 65, 55 rides with the weight bar 60 on top of the blank material until it drops into a space between blanks. When the forward edge of the oncoming blank reaches the latch or detector 64, said latch with the bar 60 is 60 carried along with the work and by its movement to the left in Fig. 5 swings correcting arm 58 downward into the path of travel of the bar 39, until the bar 39 strikes some point on the beveled end 59 of the 65 arm 58 and discontinues the movement of

the work. During this operation the pin disc 42 has been held stationary by the latch 47 contacting with a screw 44^A which is located on the pin disc 42 between the initial pin and the last pin of the pattern. The 70 correcting arm 58 is, therefore, in effect an additional controlling member having an automatically adjustable length, to determine the feed step between blanks, so that the relation of the work to pattern of pins 75 41 will be properly adjusted for locating staples in the succeeding box blank. After the bar 39 has been stopped by the beveled end 59 of the correcting arm 58, the latch 47 is withdrawn in the manner above described, permitting the disc 42 to advance the initial pin 41 of the pattern of pins to position to locate the first staple in the next blank. After the operation of the stapling mechanism between box blanks the detector 64 is withdrawn from the gap between the blanks by riding up on the inclined surface 66 of the table 67, and is returned to initial position by the tension of spring 63 which draws the weight bar 60 to the right in Fig. 90 5. This movement of the weight bar 60 to the right in Fig. 5 also swings arms 58 upward and out of the path of travel of bar 39, where it remains until again moved downward by the action of the forward edge of the next blank on the detector 64. 95

Thus the correcting mechanism enables the operator to adjust the pattern mechanism or controlling pins for locating fasteners in one blank, and to use said pattern for succeeding blanks in a continuously operating machine without readjustment, the relation between the pattern of pins and the work being automatically adjusted after the completion of each blank for accurate operation on the succeeding blank. While the correcting mechanism as illustrated is controlled by the passage of the work itself through the machine, it is obvious that the mechanism might be controlled by lugs or 100 blocks on the conveyor chains or by other devices correlated with the movement of the work. 105

During the operation of the staplers between blanks, the staple wire feed may be thrown out to render said stapling operation ineffective and avoid the driving of unnecessary staples. Such throw-out means is well known in the art and, therefore, not illustrated herein. A suitable skip mechanism is shown for example in copending application of S. F. Bauwens filed March 22, 1919, Serial No. 284,332. 110

As the work leaves the stapling mechanism, the finished blanks may be stripped from the conveyor chains onto the inclined table 67, and the wires connecting the blanks may be severed by any approved cutting mechanism properly timed or controlled. Other desirable instrumentalities 115 120 125 130

of this art, such as a conveyor brake applied to the ratchet wheel, and manually-operable means for independently adjusting or shifting the conveyor, may be embodied 6 in the machine, though unnecessary to be illustrated as they are not essential to the present invention.

Obviously the invention is not restricted to any particular structural details or mode 10 of operation, or to any particular type of wirebound box or blank construction. Furthermore, it is not indispensable that all 15 the features of the invention be used conjointly since they may be used to advantage in various different combinations and sub-combinations.

I claim as my invention and desire to secure by Letters Patent:

1. A machine for use in making wire-bound boxes comprising, in combination, fastener-setting mechanism; means to cause relative progression between said mechanism and a succession of work assemblies; means controlling the progression to locate fasteners where desired in the work including a pattern of controlling members for a work assembly and means to control said pattern to locate fasteners according to said pattern in each of a succession of work assemblies 30 regardless of irregularity in the spaces between work assemblies.

2. A machine for use in making wire-bound boxes comprising, in combination, fastener setting mechanism; means to cause relative progression between said mechanism and the work; means controlling the progression to locate fasteners where desired in a work assembly; and means controlling said last named means to effect a like location of fasteners in a succession of variably spaced work assemblies without stopping the machine.

3. A machine for use in making wire-bound boxes comprising, in combination, fastener-setting mechanism; means to cause relative progression between said mechanism and the work; and cooperating means, the relation of which to the work is automatically determined by the work, regulating the progression for controllably positioning fasteners; said machine being adapted to operate uninterruptedly upon a succession of work assemblies.

4. A machine for use in making wire-bound boxes comprising, in combination, fastener-setting mechanism; means to cause relative progression between said mechanism and the work; cooperating fastener-positioning means automatically regulating the progression; and means controlled by the progression for automatically establishing a given relation of said fastener-positioning means to the work; said machine being adapted to operate uninterruptedly upon a succession of work assemblies.

5. A machine for use in making wire-bound boxes comprising, in combination, fastener-setting mechanism; means to cause relative progression between said mechanism and the work; automatic fastener-positioning mechanism, comprising pattern means and means controlled thereby for determining relative movements between the work and the wire-fastening mechanism, to effect a disposition of fasteners according to the pattern; and automatic means controlled in accordance with the progression for effecting a given relative adjustment between the pattern and each of a succession of work-assemblies on which the fasteners are to be so disposed without stopping the machine. 70 75 80

6. A machine for use in making wire-bound boxes comprising, in combination, fastener-setting mechanism; means to cause relative progression between said mechanism and the work; cooperating means determining a special relationship of a succession of applied fastenings; and independent automatic means for effecting a given relationship between said last-named means and the work to which said fasteners are to be applied without stopping the machine. 85 90

7. A machine for use in making wire-bound boxes, comprising, in combination, fastener-setting mechanism; means to cause relative progression between said mechanism and the work; cooperating fastener-positioning means; and work-controlled means for automatically relating the work thereto without stopping the machine. 95 100

8. A machine for use in making wire-bound boxes, comprising, in combination, fastener-setting mechanism; means to cause relative progression between said mechanism and the work; cooperating fastener-positioning means automatically regulating the progression, for controllably positioning fasteners; and work-engaging means and means actuated thereby for relating the work to said fastener-positioning mechanism without stopping the machine. 105 110

9. A machine for use in making wire-bound boxes comprising, in combination, fastener-setting mechanism for wiring box material; means to cause relative progression between said mechanism and the work; and cooperating means automatically controlled by the work for similarly relating successive work assemblies with the binding-wire applying means without stopping the machine. 115 120

10. A machine for use in making wire-bound boxes comprising, in combination, fastener-setting mechanism for wiring box material; means to cause relative progression between said mechanism and the work; cooperating means for varying the progression; and independent means automatically controlled in accordance with the progression of the work for establishing a given re- 125 130

lation between said last-named means and each of successive work assemblies without stopping the machine.

11. A machine for use in making wire-bound boxes comprising, in combination, fastener-setting mechanism for wiring box material; means to cause relative progression between said mechanism and the work; cooperating means regulating the progression; and independent automatic means for relating the same with the work without stopping the machine.

12. A machine for use in making wire-bound boxes, comprising, in combination, fastener-setting mechanism for wiring box material; means to cause relative progression between said mechanism and the work; cooperating means regulating the progression; and work-engaging means and means actuated thereby for definitely relating each of successive work-assemblies to the fastener setting mechanism for the wiring operation without stopping the machine.

13. A machine for use in making wire-bound boxes comprising, in combination, cooperating binding-wire applying and fastener-setting mechanism and means to cause relative progression between said mechanism and the work, in a continuously-operating organization for wiring successive work-assemblies; and cooperating means, including work controlled means, for automatically regulating the progression for controllably disposing fasteners on successive assemblies.

14. A machine for use in making wire-bound boxes comprising, in combination, cooperating binding-wire applying and fastener-setting mechanism and means to cause relative progression between said mechanism and the work, in a continuously-operating organization for wiring successive work-assemblies; pattern means for controlling the relative progression for a work assembly and cooperating mechanism, including means for automatically establishing a given relation between the fastener-setting mechanism and each successively presented work-assembly, for effecting a disposition of fasteners on the respective assemblies according to said pattern regardless of irregularity in the spaces between successive assemblies.

15. A machine for use in making wire-bound boxes comprising, in combination, cooperating binding-wire applying and fastener-setting mechanism and means to cause relative progression between said mechanism and the work, in a continuously-operating organization for wiring successive work-assemblies; cooperating fastener-positioning mechanism comprising pattern means by which the progression is controlled to dispose fasteners in accordance with the pattern; and automatic means for effecting a given adjustment between each assembly and said pattern means re-

gardless of irregularity in the spacing of said assemblies.

16. A machine for use in making wire-bound boxes comprising, in combination, cooperating binding-wire applying and fastener-setting mechanism and means to cause relative progression between said mechanism and the work, in a continuously-operating organization for wiring successive work-assemblies; and cooperating fastener-positioning mechanism comprising pattern means by which the progression is controlled to dispose fasteners in accordance with the pattern; and independent means controlling the progression in the interval between presentation of the successive assemblies to the fastener-setting mechanism.

17. A machine for use in making wire-bound boxes comprising, in combination, cooperating binding-wire applying and fastener-setting mechanism and means to cause relative progression between said mechanism and the work, in a continuously-operating organization for wiring successive work-assemblies; and fastener-positioning mechanism, comprising successively presented controlling members and means controlled thereby regulating the progression during the application of fasteners to a work-assembly; and means independently regulating the progression during the interval between successive work-assemblies to relate said controlling members properly to the succeeding assembly.

18. A machine for use in making wire-bound boxes comprising, in combination, cooperating binding-wire applying and fastener-setting mechanism and means to cause relative progression between said mechanism and the work, in a continuously-operating organization for wiring successive work-assemblies; and cooperating fastener-positioning mechanism, comprising pattern means by which the progression is controlled to dispose fasteners in accordance with the pattern; and means operative in the interval between presentation of successive assemblies to the fastener-setting mechanism for rectifying relationship between the fastener-positioning mechanism and the work, thereby properly relating the fastener-setting mechanism and the work.

19. A machine for use in making wire-bound boxes comprising, in combination, fastener-setting mechanism; instrumentalities for supplying binding-wire to be secured by said mechanism to box-forming material progressively subjected to the operation of said mechanism; means to cause relative progression between said mechanism and the work; cooperating means automatically regulating the progression for controllably disposing individual fasteners of a work-assembly; and automatic correcting means for effecting a relative adjust- 130

ment between the fastener-positioning mechanism and the work thereby maintaining a given relation of the work and fastener-setting mechanism upon successive 5 work-assemblies.

20. A machine for use in making wire-bound boxes comprising, in combination, cooperating work-feeding and binding-wire-applying and fastener-setting mechanism in a continuously operating organization for wiring successively presented work assemblies; means constructed and arranged for causing the binding wire for each assembly to be secured at a plurality of points 10 in a selected variable spacial relationship, and cooperating means for positioning each successively presented assembly relative to the fastener-setting mechanism to receive the fasteners in like spacial relationship regardless of variation in spaces between work 15 assemblies.

21. A machine for use in making wire-bound boxes comprising, in combination, binding-wire-applying and fastener-setting 20 mechanism; means for presenting box-forming assemblies successively thereto; means constructed and arranged for fastening binding wire to each assembly at a plurality of variably spaced points; and automatic 25 means for positioning each assembly relative to the fastener-setting mechanism to receive fasteners in like relation to the work regardless of variation in spaces between work assemblies.

30 22. A machine for use in box making, which comprises, in combination, fastener-applying mechanism; means to produce relative progression between said mechanism and the work; a series of controlling 35 members and means successively controlled thereby regulating the progression during the application of a number of fasteners; said series of controlling members repeating their control for regulating to application 40 of fasteners upon successive work-assemblies; and automatic means variably regulating the progression in the interval between repetition of control by said members, properly relating said members to a 45 succeeding work-assembly.

50 23. A machine for use in box making, which comprises, in combination, fastener-applying mechanism; means to produce relative progression between said mechanism and the work; a series of controlling 55 members and means successively controlled thereby regulating the progression during the application of a number of fasteners; said series of controlling members repeating their control for regulating to application 60 of fasteners upon successive work-assemblies; and automatic means variably regulating the progression in the interval between repetition of control by said members, properly relating said members to a 65

succeeding work-assembly, said last-named means including a cam-shaped controlling member and means controlled in accordance with the passage of the work for variably presenting the same to the means which is 70 normally controlled by the said series of members.

24. A machine for use in making boxes which comprises, in combination, fastener-applying mechanism; means to produce relative progression between said mechanism and the work; and a set of controlling members and means successively controlled thereby for regulating the progression; said set of controlling members including a relatively adjustable member; and automatic means controlling the adjustment thereof. 75

25. In a box machine, the combination of fastener-setting mechanism; work-engaging means; means for relatively moving said parts for progressive presentation of the work to said fastener-setting mechanism; said elements constructed and arranged to provide a continuously-operating organization for operation upon successive box-forming assemblies; means automatically controlling the progression to effect a desired disposition of the fasteners; and automatic means for establishing a given relation between said last named means and 95 each of a succession of variably spaced work-assemblies.

26. In a box machine, the combination of fastener-setting mechanism; means for progressively presenting box-forming material 100 thereto to receive fasteners at successive points; pattern means controlling the presentation for controllably positioning fasteners; and automatic means for maintaining a given relation between the work and 105 pattern means without stopping the machine.

27. In a box machine, the combination of fastener-setting mechanism; work-engaging means; means for relatively moving said parts for progressive presentation of the work to said fastener-setting mechanism; means automatically controlling the progression to effect a desired disposition of the fasteners; and work-controlled means for establishing a given relation between said last named means and each of successively presented work-assemblies without stopping the machine. 115

28. In a box machine, the combination of fastener-setting mechanism; means for presenting a succession of variably spaced work-assemblies thereto; means determining a spacial relationship between applied fasteners in a work assembly; and automatic 120 means for relatively adjusting said last named means to each successively-presented assembly without stopping the machine.

29. A machine for use in making wire-bound boxes comprising, in combination, 125

means including fastener-setting mechanism for applying binding wire to box parts; means to cause relative progression between said mechanism and the work; pattern mechanism for controlling said progression to locate individual fasteners; and a correcting device for adjusting the relation of said pattern mechanism to successively submitted work-assemblies without stopping the machine.

30. A machine for use in making wire-bound boxes comprising, in combination, means including fastener-setting mechanism for applying binding wire to box parts; means to cause relative progression between said mechanism and the work; means automatically controlling the progression to locate individual fasteners; and a correcting device for said last named means controlled by the passage of the work.

31. A machine for use in making boxes comprising, in combination, fastener-setting mechanism; means for relatively advancing the work; frictionally or yieldingly driven means carrying a series of controlling members; means for successively stopping said last-named means to present said controlling members successively in controlling position; a reciprocatory element having its movement successively controlled by said members; and means controlled by said element for determining relative work movements.

32. A machine for use in making wire-bound boxes comprising, in combination, fastener-setting mechanism; means to supply binding wire thereto to be progressively fastened to the work; means to cause relative progression between said fastener-setting mechanism and the work; and independent automatic fastener-positioning mechanism comprising a revolving series of controlling members of variable lengths and means successively controlled thereby for regulating the progression in accordance with the lengths of said members.

33. A machine for use in making wire-bound boxes comprising, in combination, fastener-setting mechanism; means to supply binding wire thereto to be progressively fastened to the work; means to cause relative progression between said fastener-setting mechanism and the work; and automatic fastener-positioning mechanism to control the location of fasteners in a succession of work-assemblies comprising a series of controlling elements, said series including an automatically adjustable element, and means successively controlled thereby for regulating the progression.

34. A machine for use in making wire-bound boxes comprising, in combination, fastener-setting mechanism; means to supply binding wire thereto to be progressively fastened to the work; means to cause rela-

tive progression between said fastener-setting mechanism and the work; and automatic fastener-positioning mechanism to position fasteners in a succession of work assemblies comprising a series of controlling members for a work assembly coming repeatedly into action, and a relatively adjustable element; to set the series in proper relation to control the disposition of fasteners upon successive work-assemblies.

35. A machine for use in making wire-bound boxes comprising, in combination, fastener-setting mechanism; means to supply binding wire thereto to be progressively fastened to the work; means to cause relative progression between said fastener-setting mechanism and the work; and automatic fastener-positioning mechanism, including a toggle for varying the progression, and automatically-controlled means for operating the toggle.

36. In a box machine, the combination of work-supporting means; fastener-setting means; and means to cause relative movements therebetween comprising a ratchet-feed mechanism, a toggle, and means for operating the toggle to determine the period of engagement of the ratchet members.

37. In a box machine, the combination of work-supporting means; fastener-setting means; and means to cause relative movements therebetween comprising a pawl and ratchet, a constant stroke driver for the pawl, and a connection between the driver and pawl adapted to be variably broken during a drive stroke.

38. A machine for use in making wire-bound boxes comprising, in combination, fastener-setting mechanism; means to supply binding-wire to be fastened by said mechanism; and means to cause relative step movements between said mechanism and the work comprising a ratchet, a pawl, an actuator having a regulable connection with said pawl, and means to break said connection during a drive stroke.

39. A machine of the class described comprising, in combination, fastener-setting mechanism; work-engaging means; and means to cause relative step movements therebetween comprising a ratchet, a pawl, an actuator having constant connection with said pawl, and automatic means to render said connection effective only during selected periods in the operation of the machine.

40. In a box machine, the combination of a work-support; instrumentalities for operating upon the work; and means to cause relative step movements between the work and said instrumentalities comprising a ratchet, a pawl, an actuator having connection with said pawl, and automatically controlled means to break said connection during a drive stroke of the actuator.

41. In a machine of the class described, the combination, with fastener-setting mechanism, of means for causing relative progression between said mechanism and the work including a ratchet, a pawl, an actuator having a toggle connection with said pawl, and automatically controlled means for operating said toggle. 40
42. In a box machine, the combination of a work-support; mechanism for operating upon the work; means to cause relative step movements between said mechanism and the work, comprising a ratchet, a pawl, an actuator having a regulable connection with said pawl; and automatic means to vary the step movements comprising a series of controlling members and means controlled thereby for rendering said connection ineffective during a drive stroke of the actuator and before its termination. 45
43. In a box machine, the combination of a work-support; mechanism for operating upon the work; and means to cause relative step movements between said mechanism and the work, comprising a ratchet, a pawl-carrying lever, a driver, and a toggle connection between said pawl-carrying lever and said driver; and automatic means for operating said toggle connection to determine the period of engagement of the pawl and ratchet. 50
44. A machine for use in making boxes comprising, in combination, work-supporting means; fastener-setting means; and step-feed mechanism to cause relative movements between the work and said fastener- 55
- setting means, including a toggle for varying its effect; and means including a series of successively-acting controlling members for operating said toggle. 60
45. A machine for use in making wire-bound boxes comprising, in combination, fastener setting mechanism; means to cause relative progression between said mechanism and a succession of work assemblies; means controlling the progression to locate fasteners where desired in a work assembly; and means controlling the progression during the time a space between work assemblies is passing the fastener-setting mechanism whereby a like location of fasteners will be effected in a succession of work assemblies. 65
46. A machine for use in making wire-bound boxes comprising, in combination, fastener setting mechanism for applying binding wire to box parts progressively subjected to the action thereof; and means to feed the work in steps of controlled length to locate fasteners where desired therein, including a pattern of feed controlling members for a unit of work adapted to operate uninterruptedly to control the feed movements of a succession of units of work, and automatically operating means to properly adjust the relationship between said pattern and each of a succession of units of work, whereby fasteners may be located in each unit according to said pattern. 70

In testimony whereof I have signed my name to this specification.

D. A. LANDERS.
